Att'y.

UNITED STATES PATENT OFFICE

HENRI MARIE MATHIEU DE BOISSAC, OF ST. GERMAIN EN LAYE, FRANCE, ASSIGNOR TO
THE SOCIETY PIERRE REMY & CIE, OF CLICHY, FRANCE

CLOSURE

Application filed April 14, 1930, Serial No. 444,250, and in Belgium January 31, 1930.

The present invention relates to closures and, more particularly, to stoppers or covers for bottles.

One of the objects of the invention is to provide an elastic female element (stopper or cover) designed to engage by rotary movement with a rigid male element so that rotation of the female element beyond a predetermined point tends to lock the latter in position.

Other objects will appear in the course of the detailed description now to be given with reference to the accompanying drawings, in which:

15 Fig. 1 represents, in elevation, a female element formed in accordance with one constructive embodiment of the invention;

Fig. 2 is a diametrical section through the female element shown in Fig. 1;

20 Fig. 3 is an elevation of a second form of female element;

Fig. 4 is a section through the female element shown in Fig. 3;

Fig. 5 is a diagram representing the elastic 25 deformation of a female element when moved towards closed position;

Fig. 6 represents, in elevation, a male element (mouth of a bottle) formed in accordance with one embodiment of the invention;

30 Fig. 7 is a section taken on line 7 of Fig. 6;

Fig. 8 is a plan of the male element shown in Fig. 6;

Fig. 9 illustrates another form of male 35 element.

Referring to Figs. 1 to 5 of the drawings, there is shown a flexible (elastically deformable) shell or female element *a* whose vertical edges are provided with three or more 40 equidistant indentations or internal extensions *b* formed, as in Figs. 1, 2 and 5, so as to present an arcuate edge continuous with the free edge of shell *a* or, as in Figs. 3 and 4, so as to present an arcuate edge spaced from 45 the free edge of shell *a*, said arcuate edges, in both cases, being, preferably, convex with relation to the top of shell *a*.

Referring now to Figs. 6 to 9, there is shown the mouth of a bottle or male element 50 *c*, provided (A) with extensions *d* shaped so

that the "active" surface thereof (i. e. the one contacting with indentations *b*) (1) forms an angle with the axis of the bottle (60°, for example, Fig. 7), (2) presents sections, in cylinders coaxial with the bottle mouth, of 55 helical elements of very slight inclination (Figs. 6 to 9), and (3) so that, in plan, it presents a curve increasing in radius in the direction of rotation of cap *a* and then decreasing,—and (B) with an abutment *e* limiting the rotatory movement of cap *a*.

Indentations *b* and extensions *d* should be formed so that, when cap *a* is screwed onto mouth *c*, the cap is first elastically deformed (dotted line position Fig. 5) into a "triangular" shape as elements *d* and *b* ride over one another and then, once indentations *b* pass the point of maximum curvature of elements *d*, springs back partially towards its original shape as it abuts against elements *e*. Yieldable liners *a* are thus drawn down snugly 65 onto the top edge of mouth *c*, and cap *a*, having moved past its position of maximum deformation, cannot detach itself. The term "radius" as used in the claims, refers to the 70 distance from the central vertical axis of the bottle.

What I claim is:—

1. In a closure, a male element having a plurality of external extensions formed 80 thereon whose radii increase towards a maximum in a predetermined direction then decrease, said male element having abutments formed thereon adjacent the portions of said external extensions of decreasing radius, and a deformable female element having a plurality of internal extensions positioned to ride over said external extensions when said female element is rotated on the male element in the direction of increasing radius of 85 said external extensions, said internal extensions being formed so as to be first spread apart by said external extensions and then move towards one another and engage said abutments when the points on said external extensions of maximum radius have been passed.

2. In a closure, a male element having a plurality of external extensions formed thereon whose radii increase toward a maximum 100

in a predetermined direction and then decrease, said external extensions having a slightly helical form, said male element having abutments formed thereon adjacent the portions of said external extensions of decreasing radius, and a deformable female element having a plurality of internal extensions positioned to ride over said external extension when said female element is rotated on the male element in the direction of increasing radius of said external extensions, said internal extensions being convex relatively to said external extensions when the former and the latter are in engagement, said female element being dimensioned so that said internal extensions are first spread apart by said external extensions and then move toward one another and engage said abutments when the points of said external extension of maximum radius have been passed.

In testimony whereof I affix my signature.
HENRI MARIE MATHIEU de BOISSAC.
